DRY CELL

Otto Karl Reinhardt, Jamaica, and John William Baer, Elmhurst, N. Y., assignors to Bond Electric Corporation, Jersey City, N. J., a corporation of Delaware

Application March 30, 1933, Serial No. 663,476

4 Claims. (Cl. 136—133)

This invention relates to dry cells and more particularly to dry cells of the kind commonly known as No. 6 or 6" cells such as are used for enunciator circuits, telephone circuits and the like, although not so limited. Heretofore, the cup shaped container of cells of this type has been closed either by a layer of wax or sealing compound. Were a metallic closure of thin sheet steel used, electrolyte would frequently travel up the wall of the cup in the upper portion of the dry cell and attack such metallic closure and rapidly corrode it.

The present invention has for one of its objects a metallic closure for a dry cell which is not attacked by the electrolyte. Accordingly, the closure is formed of zinc which is not corroded by the electrolyte.

Another object of the invention is to secure a metallic closure of this invention to the dry cell cup.

It is also an object of the invention to seal the junction of a metal closure with the rim of the cup.

The invention also seeks to insulate a metallic closure from the central terminal or binding post thereon.

Still another object of the invention is to insulate the metallic closure from the central electrode in an effective and novel manner.

The invention also has for its object to provide a slightly appearance to the top of a dry cell without adopting the more expensive expedient of enamelling or otherwise coloring or decorating the top and at the same time to protect the metal top over its entire surface.

The invention also seeks a closure which is practical from the standpoint of ease and cheapness of manufacture and durability and practicability in use.

In carrying the invention into effect, in accordance with one aspect, a metallic disc is carried by but insulated from the central electrode of the cell and rests, at its periphery, on an inwardly directed shoulder on the cup wall. The closure is made of sheet zinc, which is unaffected by the electrolyte should any reach the surface thereof, in use. A zinc closure has never, heretofore, been used due to many considerations. Superimposed upon the metal disc is a disc or annulus of compressible insulating material of substantially the same diameter as the metal disc. These two discs are suitably clamped to the central electrode and are secured to the wall of the cup preferably by turning over the edge of the cup inwardly onto the periphery of the insulating disc to clamp both discs to the shoulder. Thus, by means of the

yielding non-metallic member with which the metal top is clamped, a tight seal is effected.

These and other objects of the invention and the means for their attainment will be more apparent from the following detailed description, taken in connection with the accompanying drawings illustrating various embodiments by which the invention may be realized, and in which:

Figure 1 shows a dry cell having the upper portion of the cup broken away and the closure in section;

Figure 2 shows a modification of the invention;

Figure 3 shows improved means facilitating assembly of the structure; and

Figure 4 shows still another modification of Figure 1.

The invention is shown as applied to the so-called No. 6 or 6" dry cells of the type commonly employed in enunciator circuits, telephone circuits and the like, but is applicable in whole or in its several aspects to any dry cell. A metallic cup 1, conveniently of zinc, has a groove 2 rolled therein to form an inwardly directed bead or shoulder 3 proximate the rim or mouth of the cup. The cup contains, as is usual, a suitable composition comprising a depolarizing mix (not shown) packed about a central carbon rod electrode 4, which projects upwardly, preferably, to about the transverse plane including the bead 3.

In the illustrated embodiment, a metallic binding post 7 is shown as protruding from the upper end of the carbon electrode 4. Obviously, the invention is not restricted to the form of conductive terminal member by which electrical connection is made with the carbon electrode.

In Figures 1, 3, and 4, there is shown, encircling the conductive member 7, a bushing 8 (Figure 1) of insulating material, such as fibre. The bushing conveniently rests upon the carbon electrode 4 and is formed with a central aperture 9 preferably snugly receiving the binding post 7.

In Figure 1, the bushing 8—10 is illustrated as formed with an upwardly directed cylindrical boss 10 and the laterally extending portion 8 of the bushing supports a disc-like metallic closure 12. Closure 12 is formed with a central aperture 13, of a diameter substantially to receive the bushing portion 10 and the edge of the aperture rests upon the laterally protruding portion 8. Thereby is the metallic closure 12 spaced from the binding post 7. Closure 12 has a diameter substantially equal to the interior diameter of the cup 1 and its peripheral edge rests on the bead 3. The metallic closure 12 and bushing 8—10 may thus be

readily assembled and the metallic closure 12 is conveniently centered by the boss 10. Preferably, the upper surfaces of the boss 10 and metallic closure 12 lie in the same plane.

- 5 The bushing 18 shown in Figure 3, is disc-like in form with a downwardly depending flange 19. At its periphery, the interior diameter of the flange is substantially equal to the external diameter of the electrode 4 so that it may be readily 10 inserted thereover and centered thereby so that the holes for the terminal member 7 are in register. In Figure 4, the bushing 20 is shown without the flange.

Superimposed upon the metallic closure 12, there is shown, in Figures 1, 3, and 4, a disc-like member 14 of insulating material, also of substantially the same diameter as the metallic closure and superimposed thereon. This closure 14 is formed with a central aperture, preferably, 20 snugly receiving the binding post 7.

Superimposed upon the closure 14 of insulating material is a washer 15 preferably metallic, by which the closures and bushing are clamped to the carbon electrode. The washer 15 is conveniently of an inverted dish shape and of relatively thin metal, and the binding post 7, in Figures 1 and 3, is shown as formed with a flange 16 which, when the binding post is inserted in the end of the carbon electrode 4, clamps the 25 bushing and closures together. In lieu of the flange 16, a nut 22, Figures 2 and 4, may serve a similar purpose. The pressure exerted by the flange 16 and nut 22 causes a distortion of the metallic washer 15 and forces the free edge of 30 the washer into the insulating disc 14, thus affording an effective joint and seal at that point.

In Figures 1, 3, and 4, the free edge 17 of the cup 1 is shown as turned inwardly and downwardly over and into the closure 14 to compress 40 the insulating material of which the closure is formed and to clamp the closures 14 and 12 to the bead 3. Furthermore, the pressure of gases, within the cell, which occur when the cell is in use, force the metallic disc 12 and therewith the 45 fibre disc 14 upwardly into the inturned edge so that as the pressure is increased, the seal becomes tighter.

The closure 14 of insulating material is, in effect, an annulus of sealing material which is 50 preferably distortable and yielding whereby the joint between the metallic closure and the metallic cup is effectively sealed. There is also provided by this construction insulating material between the washer 15 and the metallic closure 55 12. Obviously, the non-metallic member 14 need not be integral, but, Figure 4, may comprise an annulus 14' clamped by the flange 17 and a bushing 14" clamped by the washer 15.

In the modification of Figure 2, the metallic 60 closure 24 is formed at its periphery with an upturned flange 25 to be received within the upstanding rim 26 of the cup, 27 above the bead 3. The two flanges 25 and 26 may conveniently be soldered together.

65 The metallic closure 24 is conveniently inverted dish shaped and rests upon a bushing 20 of any suitable kind. Superimposed upon the closure 24 is another bushing 28 into which the edge of the washer 15 is forced by the nut 22 to 70 seal the joint, as has been explained.

The invention is obviously not limited to a flange 16 on the binding post 7 but any means is equally applicable which is carried thereby and which engages and forces the rim of a washer 75 into the insulating material.

In every instance, the metallic closture of this invention is formed from a sheet of zinc. Heretofore, in smaller cells, metallic closures have been of sheet steel. Electrolyte crawling up the walls of the cup has come into contact with the metal closure and quickly corroded it causing a leak so that the cell has quickly deteriorated. Zinc is not attacked by the electrolyte but manufacturing difficulties have prevented its use heretofore. With the method of securing the closure as illustrated herein, practical difficulties have been surmounted and an improved cell has resulted.

10 Various modifications will occur to those skilled in the art in the composition, configuration and disposition of the component elements going to 15 make up the invention as a whole, as well as in the omission of or a substitution for one or more of the elements illustrated, or selection of elements of the several embodiments illustrated into an operative combination, and no limitation is 20 intended by the phraseology of the foregoing description or illustration in the accompanying drawings.

What is claimed is:—

1. In a dry cell, a metallic cup shaped container 25 electrode having an inwardly directed bead rolled in the cup wall near the edge thereof, a substantially centrally disposed carbon electrode therein having an upwardly projecting metallic binding post, a disc-like closure of the same metal as the 30 container electrode having a diameter substantially equal to the interior diameter of the cup and resting on the bead, means to insulate the closure from the central electrode, a disc-like closure of insulating material of substantially the 35 same diameter as the metallic closure and superimposed thereon, said closure of insulating material being formed with a central aperture receiving the binding post, an inverted cup-shaped bushing of relatively thin metal superimposed 40 on the closure of insulating material and formed with a central aperture receiving the binding post, said binding post having means to engage the metallic bushing to retain the bushing and discs on the electrode and force the edge of the 45 inverted cup into the insulating material, the edge of the cup being turned inwardly over the closure of insulating material to clamp the closures to the bead.

2. A dry cell comprising an open top zinc cup 50 having a groove rolled in its wall adjacent its upper end to form an inwardly extending integral annular shoulder, an electrode at the center of the cup and provided with a metallic binding post projecting therefrom out of the open end 55 of the cup, a closure for the open end comprising two superposed discs fitted within the open end of the cup, the inner disc being of zinc and engaging at its periphery on the shoulder and having an opening at its center through which the 60 binding post projects in spaced relation to the outlining edge of the opening and the other disc being of insulating material and of substantially the same diameter as the zinc disc and snugly fitting around the binding post, the upper edge 65 of the cup being turned inwardly to engage the upper disc and thus secure the closure to the cup, and an insulating bushing located between the zinc closure disc and the adjacent end of the electrode.

3. In a dry cell, a metallic cup-shaped container electrode, a substantially centrally disposed electrode therein having a conductive member at its upper end, a bushing of insulating material resting on the central electrode and formed with

5 a central aperture receiving the conductive member, a disc-like closure of the same metal as the container electrode having a diameter substantially equal to the interior diameter of the cup and resting on the bushing and formed with a central aperture of a diameter greater than the conductive member to be spaced therefrom, a bushing of distortable insulating material superimposed on the metallic closure, said bushing of 10 insulating material being formed with a central aperture receiving the conductive member, and clamping means to retain the bushings and disc on the central electrode comprising an inverted cup-shaped metallic washer, means carried with 15 the conductive member to force the rim of the cup-shaped washer into the superimposed bushing and means to seal the rim of the closure with the rim of the container.

4. In a dry cell, a metallic cup-shaped container electrode having an inwardly directed shoulder near the upper edge thereof, a central electrode, a binding post carried thereby a disc-like metallic closure having a diameter substantially equal to the interior diameter of the cup and resting on the shoulder, an annular member of substantially yielding non-metallic material of substantially the same diameter as the diameter of the closure superimposed thereon, means 10 to insulate the closure from the central electrode, the edge of the cup being turned inwardly over the non-metallic annular member, a thin metal washer of inverted dish shape encircling the binding post and bearing at its lower edge 15 on the non-metallic annular member.
